UNITED STATES PATENT OFFICE

CARL FRITZ SJÖMAN AND CARL GUSTAF PETTERSSON, OF STOCKHOLM, SWEDEN, AS-SIGNORS TO J. & C. G. BOLINDERS MEKANISKA VERKSTADS AKTIEBOLAG, OF STOCKHOLM, SWEDEN, A CORPORATION

FUEL-INJECTING APPARATUS FOR INTERNAL-COMBUSTION ENGINES AND THE LIKE

Application filed April 2, 1921, Serial No. 458,158, and in Sweden January 22, 1921.

As is well known, the fuel on being injected into the ignition chamber of internal combustion engines is generally spread so as to be atomized, whereby it readily minglest with the air, this causing a more rapid ignition and complete combustion thereof.

It has been found, however, that the spreading of the fuel is essential particularly when the motor is being started, or is running idle, that is to say when the walls of the ignition chamber have a comparatively low temperature. If the load on the motor is normal or high, the walls of the ignition chamber being then intensely heated, spreading of the fuel is required only in a lesser degree, or, perhaps not at all.

Nevertheless it has not been possible heretofore to use anything but the same degree of spreading in all instances, and consequently it has been necessary, in the case of a high or even normal load on the motor, to cool the walls of the ignition chamber either by providing the chamber with a cooling jacket, or by injecting water together with the fuel into the ignition chamber. However, this cooling is often not sufficient to avoid the drawbacks caused by the increased heating of the ignition chamber, and it will be found particularly difficult to keep the ignition chamber at so low a temperature by the cooling as to prevent premature ignition.

It is therefore a desideratum to so change the injection of the fuel at any instant that the injection is taking place with a greater or lesser degree of spreading, or perhaps without any spreading at all.

Now, the present invention provides for a control of the spreading of the fuel when the motor is being started, or is running, or at the start as well as during the operation thereof. Thus, for instance, the fuel may be introduced with a high degree of spreading at the start or when the motor is running idle, the spreading being then, for example, effected at an angle up to 90° , whereas, when the motor is running at the normal or a high load, the spreading angle may be reduced to 15° , or be entirely eliminated, so that the fuel will be introduced into the ignition chamber as a straight jet.

Thus the invention is principally characterized by the apparatus required for the injection being so devised that the spreading of the fuel may be varied, for instance in accordance with the varying load on the motor.

The invention is carried into effect in the most efficient way by the employment of a spreading member which is provided with a hollow on the inside of the nozzle outlet of the injecting apparatus and substantially tangential channels leading to the said hollow, which channels impart a powerful rotational impulse to the fuel when it is led into the hollow. By making the said member displaceable or rotary, in accordance with the invention, so that the fuel may be introduced into the hollow in some other way than through the tangential channels, or, in other words, so that the fuel flows past the same, the desired result is obtained, namely that the fuel is introduced into the hollow without a rotational impulse, and consequently leaves the nozzle outlet without rotating. However, the rotation and the spreading may be maintained to a certain degree by adjusting the adjustable part of the nozzle only so much as is necessary to allow part of the fuel to pass through the tangential channels, while the remaining portion flows past the same.

The accompanying drawing illustrates an embodiment of the invention. Fig. 1 is a longitudinal section of a fuel injecting apparatus arranged according to the invention. Fig. 2 is an elevation of the adjustable member devised in accordance with the invention. Fig. 3 is an endwise view of the same member. Fig. 4 is a section illustrating the position of the adjustable member after the adjustment wherein the fuel is not actuated so as to be rotated.

According to the drawing, the injecting apparatus consists of an outer sleeve-like portion 1 having a supply 2 from a fuel tank arranged at the side thereof. Centrally arranged within the sleeve 1 is the spindle 3 the diameter of which is so dimensioned as to leave a free space around the spindle between the latter and the sleeve. The spindle is adapted to be screwed in the sleeve and

is provided at its inner end with a cylindrical enlargement 5 bearing snugly against the inside of the sleeve, the plane end surface of the said enlargement abutting tightly against the bottom 6 of the sleeve. Arranged in the 5 said bottom 6 is the nozzle outlet 7. Provided in that surface of the cylinder 5, which abuts against the bottom 6, is a hollow or cavity 8 having two tangentially arranged channels 9 leading thereto, the said channels 9 communicating with channels 10 provided in the 10 cylindrical surface of the member 5 and communicating with the passage 11.

As long as the spindle assumes the position 15 according to Fig. 1 with the member 5 bearing tightly against the bottom 6, the fuel pressed forth through the channels 10 is forced into the tangential channels 9 which impart a rotary motion to the fuel, whereby the latter is spread when being forced out through 20 the nozzle outlet 7. The maximum degree of spreading preferably takes place at an angle of 90°.

If the spindle 3 is screwed so that the end 25 surface of the member 5 is removed from the bottom 6, the fuel is allowed to freely pass into the chamber between the member 5 and the bottom 6 and the nozzle outlet 7 without having to be forced through the tangential 30 channels, and consequently the fuel is not caused to rotate, and there is no spreading of the same, or, at any rate, only a reduced spreading thereof. If the spindle is adjusted so that the distance between the bottom of 35 the sleeve and the member 5 leaves room only for part of the fuel, while the remaining portion of the fuel has to pass through the tangential channels, the result will be a reduced rotational action and a spreading 40 which is decreased correspondingly. It may be found suitable to maintain such a reduced spreading also when the motor operates normally, the spreading angle being then preferably 15°.

45 As set forth, the device may be made in various ways, and among these the following may be given as an example. Thus the member 5 of the spindle may, if desired, be rotatable instead of axially displaceable, the 50 said member 5 then in the one extreme position communicating through channels with such other channels leading to the outlet 7 as may impart a rotational impulse to the fuel, in order to spread the same, whereas 55 in the other extreme position the channels of the member 5 communicate with such channels leading to the outlet that cannot bring about any rotation of the fuel.

What we claim as new and desire to secure by Letters Patent of the United States is:—

60 A fuel injecting apparatus for internal combustion engines including a sleeve having a closed end provided with an outlet opening 65 and defining an internal shoulder, a spray-

controlling member slidably fitted in said sleeve and having an end surface adapted to be pressed against or moved away from the internal shoulder, said controlling member having external channels and substantially 70 tangential channels provided in the said end surface movable against said shoulder.

It witness whereof we have hereunto set our hands.

CARL FRITZ SJÖMAN.
